UNITED STATES PATENT OFFICE

AINO JOHANNES LAHTI, OF JYVASKYLA, FINLAND

AUTOMATIC FIREARM

Application filed December 26, 1930, Serial No. 504,924, and in Finland July 5, 1930.

The invention relates to an automatic pistol in which the reaction of the gunpowder gas pressure and a spring force counter-acting the gas pressure act automatically at the firing of the pistol, thus effecting feeding in of a new cartridge, cocking of the pistol, firing off, and ejection of the empty cartridge.

The accompanying drawing illustrates schematically one way of carrying out the invention in practice, and in it:

Fig. 1 illustrates a vertical longitudinal section of the automatic pistol according to the invention.

Fig. 2 illustrates the automatic pistol in side-elevation.

Fig. 3 illustrates the cocking parts of the automatic pistol in horizontal longitudinal section.

To the butt-end of the pistol is attached the stationary barrel 31 of the pistol and around it the cooling mantle 28 of the barrel. The cartridge case 1, which is either a prismatic tube or a round container, is pushed into the feeding aperture in the butt-end 40, the cartridge case 1 being retained in the feeding aperture by means of a notch 2 in the side of the case and a corresponding latch 3 pivoted in the butt-end and acted by a spring. A feeding spring in the cartridge case 1 effects the feeding in of the cartridge in the usual manner. The locking plunger 4 of the cock acts likewise as the hammer, the said locking plunger 4 having at the rear end the shape of a piston 41, which moves in the stationary cock cylinder 25 in the butt-end 40. A helical spring guided by a pin 42 acts between the head 32 of the cock cylinder mantle 33 and the locking plunger 4. The resetting spring 8 extends into a centric bore 43 in the locking plunger 4, thus making the cock shorter. At the commencement of the firing the cocking bolt 5, fitted into the butt-end 4, is pulled backwards. At the fore end of the cocking bolt 5 there is a latch 44 protruding through a longitudinal cut 45 in the cock cylinder mantle 33 behind the piston 41 of the locking plunger 4. The locking plunger 4 thus moves against the action of the resetting spring 8 compressing same. The stop 6 of the trigger mechanism is

pressed behind the shoulder 46 of the locking plunger 4 thus retaining the plunger. The locking piston 41 has expelled the air from the cock cylinder 25 through holes 22 in the cylinder head 32. These holes 22 are furnished with a check valve made up of a disc 26 in the valve body 47, the said disc 26 being pressed against the holes 22 by a spring 27. The air escapes through an aperture 24 from the valve body 47. The pistol now being cocked the cocking bolt 5 is released and reassumes by action of the cocking bolt spring 7 its original forward position and is retained there during the firing. When the trigger 15 is pulled the stop 6 is forced downwards, the locking plunger 4 is released and moves forward by action of the resetting spring 8. Due to the check valve 26, 27 now closing the air passages 22 a vacuum is created in the cock cylinder 25, retarding the forward motion of the locking plunger 4. The mantle piece 33 of the locking cylinder 25 may be furnished with a small hole, through which air is let into the cylinder. The effect of the vacuum brake 75 may be varied by means of adjusting the size of the hole. The forward end 16 of the locking plunger 4 pushes the cartridge from the mouth of the cartridge case 1 into the cartridge chamber 17 and finally the firing 80 needle 18 at the foremost end of the locking plunger 4 strikes the percussion cap of the cartridge, thus effecting the firing off of the cartridge. The empty cartridge and the locking plunger 4 are forced backwards by 85 reaction of the gunpowder gases. The extractor 19 pulls the cartridge until the ejector notch 20 in the opposite side ejects the cartridge through the discarding aperture 21.

In the foremost part of the lock and above the mouth of the cartridge magazine the cartridge channel 50 is located. In this channel the cartridges and the front end of the bolt 4 move successively. The guiding of the empty cartridge in the said channel 50 is secured by the wall of the channel being provided with a special guiding bar 51 the inner edge of which is parallel or only slightly oblique to the longitudinal axis of the channel and located from the said axis substan-

tially the same distance as the maximum radius of the cartridge chamber 17. By this provision the empty cartridge can not, even in case the butt edge of the cartridge or the extractor 19 notch are worn, turn crosswise in the channel even to such a slight extent that the extractor 19 would loose its grip on the cartridge thus resulting in improper operation of the automatic feature. The guiding is rendered most effective by locating the guiding bar 51 diametrically opposite to the extractor 19. The cartridge is by this means trapped between the guiding bar 51 and the extractor 19 thus retaining its positive axial position. By means of the above described mechanism the empty cartridge is removed in its proper position to the ejector notch 20 which throws the cartridge out through the discarding aperture 21.

20 What is claimed is:

1. An automatic firearm operating by means of reaction pressure comprising a cartridge chamber, a cartridge channel disposed adjacent said chamber, said channel being provided with a longitudinal guiding bar, the inner edge of which is substantially parallel to the axis of said channel, said inner edge also being disposed at substantially the same distance from the axis of said channel as the radius of said cartridge chamber.

2. An automatic firearm operating by means of the reaction pressure comprising a cartridge chamber, a cartridge channel disposed adjacent said chamber, an extractor positioned in said channel, a longitudinal guiding bar also positioned in said channel diametrically opposite to said extractor, the inner edge of said guiding bar extending substantially parallel to the axis of said channel and the inner edge of said bar also being disposed at substantially the same distance from the longitudinal axis of said channel as the radius of said cartridge chamber.

In testimony whereof I affix my signature.

45 AIMO JOHANNES LAHTI.
